UNITED STATES PATENT OFFICE

92,401

DESIGN FOR AN AUTOMOBILE TIRE

Harry C. Hower, Chicago, Ill.

Application March 28, 1934, Serial No. 51,209

Term of patent 7 years

To all whom it may concern:

Be it known that I, HARRY C. HOWER, a citizen of the United States, residing at Chicago, in the county of Cook and State of Illinois, have invented a new, original and ornamental Design for Automobile Tires, of which the following is a specification, reference being had to the accompanying drawing, forming a part thereof.

In the drawing:

Figure 1 is a perspective view, partially in

dotted lines, of a tire embodying the present design; and

Figure 2 is a transverse radial section taken on the line 2—2 of Figure 1.

I claim:

The ornamental design for an automobile tire, as shown.

In witness whereof, I hereunto subscribe my name this 24th day of March, 1934.

HARRY C. HOWER.
